CLAIM

The design for a optical card reader/writer, as shown
and described.

DESCRIPTION

FIG. 1 is a front perspective view of a optical card
reader/writer showing my new design;

FIG. 2 is a front elevational view thereof;

FIG. 3 is a right side elevational view thereof, the left
side being the mirror image of the right side;

FIG. 4 is a rear elevational view thereof;

FIG. 5 is a top plan view thereof; and

FIG. 6 is a bottom plan view thereof.

FIG. 1**FIG. 2****FIG. 3**FIG. 4

FIG. 5

FIG. 6
